R. L. MILLER

PARACHUTE TOY

Filed Oct. 23, 1922.

Inventor,

Ralph L. Miller,
By Howard A. Smith,
His Attorney.

Fig. 3.

UNITED STATES PATENT OFFICE.

RALPH L. MILLER, OF DAYTON, OHIO.

PARACHUTE TOY.

Application filed October 23, 1922. Serial No. 596,257.

To all whom it may concern:

Be it known that I, RALPH L. MILLER, a citizen of the United States, residing in the city of Dayton, in the county of Montgomery and State of Ohio, have invented certain new and useful Improvements in Parachute Toys, of which the following is a specification.

It is the general purpose of my invention 10 to provide a toy ball or other object which, when thrown into the air, will open to release parachute means by which it or its parts may be slowly and safely carried to the ground.

15 The toy is simply constructed and may be economically manufactured. It may be readily thrown into the air by the hand, where it will freely open to release little parachutes or other air-floating mediums 20 which carry the toy or its parts to the ground in a manner which delights children and adults.

25 In the accompanying drawings, Figure 1 is a perspective view of my toy in the form of a two-part ball ready to be thrown into the air. Figure 2 is a vertical section taken through the same. And Figure 3 is a perspective view of one of the parts of the ball being carried to the ground by the 30 parachute which it contained.

Throughout the specification and drawings, similar reference characters denote corresponding parts.

Referring to the accompanying drawings 35 for a detailed description of one form of embodiment of my invention, the numeral 1 designates a spherical shell constructed of light material and divided into two parts. Preferably glued to the interior surface of 40 the lower part of the shell, and projecting upwardly therefrom, is an annular flange 2 over which the upper part of the shell is fitted to bring its surface flush with the outer surface of the lower part. The parts 45 of the shell thus fitted to one another, or connected in any like manner, form a ball which may be easily thrown into the air.

50 Projecting outwardly from the lower part of the shell 1 near its upper annular edge, is a pin 3 around which there may be wound the free end of a preferably elastic band 4 whose other end is knotted after being passed through a hole in the opposite side of the lower part of the shell. (See Figures 1 and 2.)

Contained within each part of the spherical shell 1 is a small parachute 5 that is made of a material that may be compressed in a small space. Secured within the top part of the shell is a disc 6 through holes 60 in which there project downwardly strings 7, 7 whose upper ends are knotted above the disc and whose lower ends are connected to the parachute 5 contained within the upper part of the shell. Similar strings 7, 7, 65 knotted at their lower ends, pass upwardly through a disc 8, secured within the lower part of the shell, for connection to the parachute 5 which it contains. While I have employed the means shown and described for 70 connecting the parachute strings or strands to the separate parts of the shell, any other means may be employed for this purpose if desired. It is also understood that any medium which is the equivalent of a 75 parachute for carrying the shell or any part of it safely to the ground, may be employed if desired.

When the parachutes 5, 5 have been compressed within the two parts of the shell 1, the upper part of the latter is forced over the flange 2 of the lower part to form a ball. The elastic band 4 is then drawn over the outer surface of the top part of the shell and then wound around the pin 3 a number 80 of times, after which it is held tightly against the pin by the pressure of one or more fingers upon it. (See Figures 1 and 2.) The shell is then thrown into the air, whereupon the free end of the band 4 will 85 automatically unwind itself from the pin 3 to permit the two parts of the shell to separate. After each part starts to descend, the parachute contained therein will open to slowly and safely carry it to the ground 90 for the amusement of the thrower and of others whose attention it attracts. The toy will not only afford pleasure to a child, but will illustrate for him some of the principles 95 of gravity and flight.

I do not wish to be limited to the details of construction and arrangement herein shown and described, and any changes or modifications may be made therein within the scope of the subjoined claims.

Having described my invention, I claim:

1. A toy comprising an object formed in two sections, parachute means between said sections, a band connected to one side of one section, and a projection on the other side 110

of said section around which the free end of said band is adapted to be wound after passing completely over the outer surface of the other section.

5 2. A toy comprising an object separable into two hollow parts, a parachute contained in each part and connected thereto, a band connected to one side of one part, and a projection on the other side of said part around 10 which the free end of said band is adapted to be wound after passing completely over the outer surface of the other part of said object.

15 3. A toy comprising a spherical shell separable into two parts, a flange on one

part over which the other part fits, a parachute contained in and connected to each part, an elastic band secured to one side of the lower part of the shell, and a pin projecting outwardly from the other side 20 of said lower part around which the free end of said band is adapted to be wound after passing completely over the other part after passing over the outer surface of the upper part of the shell.

26

In witness whereof I have hereunto set my hand this 20th day of October, 1922.

RALPH L. MILLER.

Witness:

HOWARD S. SMITH.
